FIG. 2

FIG. 3 FIG. 4 FIG. 5

FIG. 6

INVENTOR.
LEE THOMPSON
BY *A.B. Bowman*
ATTORNEY

Patented Oct. 9, 1928.

UNITED STATES PATENT OFFICE.

LEE THOMPSON, OF SAN DIEGO, CALIFORNIA.

CHANGEABLE ADVERTISING SIGN.

Application filed October 29, 1926. Serial No. 144,937.

This invention relates to improvements in an automatic advertising cabinet, and the objects of my improvements are: first, to provide a cabinet of the class described containing a plurality of panels carrying advertising matter on both side surfaces; second, to provide a cabinet of the class described having rotationally movable panels visible from either side of the cabinet; third, to provide a plurality of rotationally movable advertising panels capable of carrying advertising cards or having notices written directly on their surfaces; fourth, to provide a cabinet of the class described which is economical of space, simple and rugged in construction and reliable in operation; fifth, to provide a cabinet of the class described in which the individual panels are readily accessible and removable, and sixth, to provide a cabinet of the class described in which any objectionable flicker caused by oppositely moving panel groups is eliminated.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a front view, showing the cabinet in section, viewed in the direction of the arrows 2-2 of Fig. 2, and showing fragmentary views of the chain and a number of the upper panels; Fig. 2 is a side view in section viewed in the direction of the arrows 1-1 of Fig. 1; Fig. 3 is an enlarged fragmentary detailed elevation of one of the panels, showing an advertising card in place; Fig. 4 is an end view of the panel with a card inserted on one side; Fig. 5 is a further fragmentary elevation of the panel, showing the black writing surface and a fragmentary view of the chain with the supporting lug for the panel, and Fig. 6 is an enlarged detailed side elevation of a supporting lug, showing the method of securing to the chain.

Like characters of reference refer to similar parts and portions throughout the several views of the drawings.

The principal parts of my advertising

cabinet are the frame 1, the spindles 2 and 3, sprockets 4, 5, 6 and 7, chains 8 and 9, panels 10, motor 11, worm 12, worm wheel 13, motor supporting bracket 14, and partition 15.

The cabinet frame 1 is substantially a shallow, rectangular case, the front and rear portions of which have rectangular openings in which glass doors 1^a and 1^b are fitted, either hinged, clamped or otherwise secured, permitting their being readily opened or removed. The spindle 2 is rotatably supported in bearings 2^a and 2^b suitably secured to the lower ends of the frame sides 1^c and 1^d of the frame 1, and so positioned that the spindle 2 lies midway between the glass doors 1^a and 1^b. The bearing 2^a is mounted on the exterior of the frame side 1^c, the spindle 2 extending through the bearing 2^a and carrying on said extension a worm wheel 13 suitably secured to the spindle 2. The worm wheel 13 is driven by means of the worm 12 mounted on the shaft 11^a of the motor 11. Sprockets 4 and 5 are mounted on and secured to the spindle 2 on either side within the frame. The spindle 3 is rotatably mounted at the upper end of the frame 1, in bearings 3^a and 3^b, so positioned that the spindle 3 lies parallel to and vertically above the spindle 2. A pair of sprockets 6 and 7 are secured to the spindle 3 in vertical alignment with the sprockets 4 and 5, respectively. A pair of endless chains 8 and 9 run over these sprockets, the chain 8 cooperating with the sprockets 4 and 6, and the chain 9 with the sprockets 5 and 7. In this manner the chains 8 and 9 are movable in planes parallel and adjacent to the frame ends 1^c and 1^d, respectively. As all four sprockets are of equal size, the chains will move at a uniform rate of speed when the spindle 2 is rotated.

The chains 8 and 9 are provided with triangular shaped lugs 16 having perforations 16^a. These lugs may form part of the chain link, as more clearly illustrated in Figs. 5 and 6. They are placed at suitable intervals on one side of each chain. When assembling the latter in position on their sprockets, they are so arranged that the lugs 16 form pairs in horizontal alignment, as seen in Fig. 1. A plurality of elongated rectangular panels 10, of any suitable material, are provided with studs

10^a at their ends, as shown in Figs. 3, 4 and 5. These panels are suspended between the chains 8 and 9, the studs 10^a extending through perforations 16^a in the lugs 16. 5 Loosely mounted spacing collars 10^b are provided to prevent lateral displacement of the panels 10. An opaque partition 15, occupying a central position between the series of panels, is secured to the frame ends 1^c and 1^d in any suitable manner.

The panels 10 are provided with mat block surfaces 10^a, suitable for writing on with chalk or other material, and further with channels, formed by bent strips 10^c, secured to their edges, as illustrated in Figs. 3 and 4. The channels allow cards 17 to be slipped on and held in position on either panel surface, if desired.

In operation the pair of chains supporting 20 the panels, which carry advertisements on both surfaces, either written thereon or on cards supported thereby, are caused to move uniformly vertically across both windows in the cabinet doors. While one side of a number of the panels is visible through one window, the reverse side of a number of the remaining panels is visible through the other window. Thus, the cabinet presents to view 25 sequentially, both sides of the panels moving therein. In this manner the greatest possible advertising display is obtained.

The use of a worm drive from motor shaft to sprocket spindle enables the movement of the chains to be held at a suitable low rate 30 of speed, while permitting the use of a reasonably high speed motor.

The centrally located partition 15 obviates the disturbing effect that would otherwise be caused by the oppositely moving panel 35 groups and the objectionable flicker of light resulting therefrom.

The simple, flexible suspension allows of quick removal and replacement of panels, which is an essential feature of this class 40 of advertising cabinet.

Though I have shown and described a

particular construction, combination and arrangement of parts and portions, I do not wish to be limited to this particular construction, combination and arrangement, but 50 desire to include in the scope of my invention, the construction, combination and arrangement substantially as set forth in the appended claims.

Having thus described my invention, 55 what I claim as new and desire to secure by Letters Patent is:

1. In a unit member of a plurality of panels forming a movable group in an advertising cabinet, two blackboard faced display surfaces, channel members secured to the margins thereof, forming grooves for supporting one or more independent display members over said blackboard surfaces and studs projecting from each end of said panel for pivotally suspending same. 60

2. In an advertising cabinet of the class described, a pair of endless chains provided at spaced intervals with links having perforated projections, a plurality of panels 70 having two blackboard faced display surfaces, relatively aligned studs projecting from each end of said panels and journaled in said perforated links, channel members provided on the margin of said panels for supporting independent display cards, and means for simultaneously moving the endless chains and displaying successively opposite surfaces of said panels. 75

3. In a unit panel member of a plurality of movable panels in an advertising cabinet, two blackboard-faced display surfaces, and a pair of U-shaped channel members secured to and enveloping the upper and lower edges of said panel member and forming 80 with the surfaces thereof grooves for supporting one or more independent display members over said blackboard surfaces. 85

In testimony whereof, I have hereunto set my hand at San Diego, California, this 90 22nd day of October, 1926.

LEE THOMPSON.
